HUMIDIFIER

Willet E. Stark, East Cleveland, Ohio, assignor to
The Bryant Heater Company, Cleveland, Ohio,
a corporation of Ohio

Application July 28, 1934, Serial No. 737,432

11 Claims. (Cl. 261—15)

This invention relates to improvements in humidifiers, particularly humidifiers of such character as to be adapted especially for use in residences.

5 One of the objects of the invention is the provision of an apparatus of this kind which shall be economical in operation as well as in first cost, and one which will be effective and susceptible of automatic control.

10 Another object is the provision of a unit for this purpose which shall be compact and easily installed.

15 Still another object is the provision of automatic control means of a simple nature in which the fuel valve is indirectly operated by water pressure in the water conductor, thereby simplifying the electrical connections.

20 Other objects and features of novelty will appear as I proceed with the description of those embodiments of the invention which, for the purposes of the present application, I have illustrated in the accompanying drawings, in which

25 Fig. 1 is a vertical sectional view through the casing of a humidifier unit embodying the invention, and showing certain portions of the apparatus in section, other portions being broken away or removed for the sake of clearness.

30 Fig. 2 is a diagrammatic view illustrating particularly that part of the apparatus which is not disclosed in Fig. 1, and showing the general arrangement of the control means, and

35 Fig. 3 is a diagrammatic view of a modification.

In Figs. 1 and 2, which disclose a preferred form of the invention, a fan or blower 10 for inducing circulation of the air to be treated is shown extending through a suitable opening 11 in the side of a casing 12. The fan is driven by an electric motor 13.

40 The water to be evaporated is taken from an open pan 14, which is mounted above the jacket 15 of a water heater. The latter comprises the usual copper coil 16 and a gas burner 17. The upper end of coil 16 enters the pan 14 into which it delivers the heated water. From the pan 14 a return pipe 18 extends (outside of the jacket 15) downwardly to a union 19. The lower end of coil 16 projects through the jacket 15 and into this same union. Hence there is provided a complete water circulation system from union 19 into coil 16, up through that coil into pan 14, and back through pipe 18 to the union. Additional or replacement water is fed into this circulation system through a pipe 20, which also extends into 45 the union 19.

One side of the pan 14 is cut away to form a dam 21. A plate 22 is attached to that side of the pan and extends downwardly beyond the bottom of the pan. Water flowing over the dam 21 runs down the side of plate 22 and drips off the lower edge of that plate. A baffle plate 23 with a curved lower end prevents the current of air induced by the fan 10 from blowing water off the lower extremity of the plate 22.

24 is a screen made preferably of woven wire bent into accordian folds. It is so placed that its upper end receives the water overflowing from the pan 14. In order to stiffen the assembly, parallel screen elements 25 and 26 may be secured to the folds of the screen 24, and a bracket 27 may be employed to secure the upper end of the screen assembly in position. The lower end of the same is received within a shallow pan 28 from which a drain pipe 29 leads to the sewer.

20 A flue 30 is connected with the upper end of the jacket 15 and extends from the casing 12, preferably into a chimney (not shown) for conducting away the products of combustion. Above the pan there is a baffle plate 31, which directs some of the air downwardly to ripple the surface of the water and thereby increase or facilitate evaporation. 25 At 32 in the top of the jacket 1 have shown a flanged opening through which the humidified air may flow on its way to the premises. The casing 12 may be hung from the ceiling of a basement, and air conductor connections may be made from the opening 32 to a register centrally located in the first floor of the house, while air conductor connections may be made from the opening 11 to another register spaced from the first, through which air to be humidified is collected and caused to pass to the humidifier.

30 The gas fuel for the water heater enters the apparatus through a pipe 33. A small pipe 34 extends from pipe 33 to a constantly burning pilot 35 directly adjacent the burner 17, so that whenever gas enters the burner 17 it will be ignited by the pilot 35. There are three valves in the fuel pipe leading to the burner 17, that is a diaphragm valve 38 which is an on and off valve automatically operated, a valve 39 which is designed to control the rate of flow of the fuel in order to maintain the temperature of the water in the water heater at a desired level, and a third valve 40 which is designed to prevent the flow of fuel 45 in the event that the pilot 35 should be "out" when the fuel is turned on by valve 38.

50 The water pipe 20 leading into the humidifier may include a strainer 41 of any suitable character. In the same pipe there is an electric solenoid 55

valve 42 which is closed in the normal position. The valve piece 43 of this valve is adapted to be raised to the open position when an electric coil 44 in the valve unit is energized. A needle valve 45 is also mounted in pipe 20 and may be adjusted to regulate the rate of flow of water through the pipe.

A branch pipe 46 extends upwardly from pipe 20, and has connection with the lower part of a 10 casing 47, in which there is mounted a rubber or other diaphragm 48. This diaphragm is normally held in a lowered position by the action of a coil spring 49. The diaphragm 48 engages the lower end of a pin 50 which is slidable through 15 the upper wall of casing 47 and also through an opening in the lower part of the casing of gas valve 38. At its upper end this pin bears against the lower surface of a diaphragm 51 which normally rests upon an annular seat 52 in the valve. 20 There is a bleed hole 53 through the diaphragm in order that pressure above and below the diaphragm may be equalized, permitting the diaphragm 51 to descend and engage its seat whenever the diaphragm 48 is permitted to descend 25 and to pull the pin 50 down with it.

The valve 39, which is a valve for regulating the rate of flow of fuel, comprises a casing in which there is a chamber 54 having an intake passage 55. A second chamber 56 is separated from 30 chamber 54 by a partition 57 through which there is a circular opening. This opening is surrounded by an annular valve seat 58 on the lower side of the partition, and a valve disc 59 is adapted to engage this seat. From the chamber 56 an outlet passage 60 leads into pipe 61, which is in effect a continuation of pipe 33. A coil spring 62 tends to raise valve disc 59 and hold it against its seat on the lower surface of partition 57. A pin 63 slides through an opening in the upper wall of 35 the casing of valve 39, and bears against an adjusting screw 64 arranged within an extension of the valve casing. This screw is threaded into the enlarged lower end of a non-expanding rod 65. Screw 64 may be furnished with a pointer 45 and operator 66 for convenience in making adjustments. Rod 65 is engaged at its upper end by the closed extremity of an expanding tube 67, that is to say a tube formed of metal which expands and contracts an appreciable amount 50 with variations in temperature. The lower end of this tube is tightly mounted in the casing extension, and projects through union 19 up into return conductor water pipe 18. Changes in the temperature of the water in this pipe therefore 55 cause changes in the pressure exerted through pin 63 upon valve disc 59, thereby regulating the size of the opening between the chambers 54 and 56, and hence the rate of flow of gas through the valve. In practice the movements of the valve 60 piece 59 are very slight. This water thermostat, consisting primarily of the rod 65 and the tube 67, for controlling gas flow, is well known in the art, and forms no part of the present invention except in combination with other elements of the 65 apparatus herein disclosed.

The fuel valve 40, as previously stated, is solely for the purpose of cutting off the flow of fuel in the event that the pilot 35 should go out. This valve also forms no part of the present invention 70 except in combination with other elements, and hence it will be described quite briefly.

Within the casing of valve 40 there are two valve seats 68 and 69 arranged in horizontal alignment and spaced apart slightly. A valve disc 75 70 is adapted to engage either one of these seats,

and has a stem 71 passing through a sealing diaphragm 72, and provided at its extremity with a pair of spaced collars 73, between which is arranged a bifurcated lever 74 that is pivoted at its lower end, and at its upper end engages a 5 spring link 75 pivoted at its upper end to the casing 16. The lever 74 and the link 75 together form a toggle which operates to push the valve stem 71 in one direction or the other as soon as the toggle moves over dead center. In this way 10 the valve piece 70 is caused to engage one or the other of the two seats 68 and 69. From an intermediate part of lever 74 a link 77 extends to the lower end of a thermostatic metal strip 78 mounted at its upper end on the casing 16. A small fuel 15 tube 79 extends from the casing of valve 40, behind valve seat 69, around to a position beneath and adjacent to thermostatic strip 78, and is perforated at its extremity to constitute a pilot 20 burner 80. Thermostatic strip 78 is protected 25 from the heat of pilot 35 by a suitable barrier 81.

When the burner 17 is not operating, valve piece 70 is in engagement with valve seat 68. Now, if the gas be turned on by valve 38, gas will flow through tube 79 into pilot burner 80, 30 which will be ignited by the constantly burning pilot 35. The heat from the pilot 80 will then cause thermostatic metal strip 78 to bend into the position shown in Fig. 2, whereupon pipe 79 will be closed off and gas will be permitted to 35 flow into burner 17. The pilot 18 will then go out temporarily, permitting thermostatic strip 78 to cool off to the extent necessary to draw the toggle 74, 75 over toward dead center, when the flow of fuel through tube 79 will be resumed and 40 pilot 80 again ignited. The strip 78 will then again cause the valve disc 70 to close against seat 69. In this way the pilot 80 will be turned on and off at frequent intervals but the valve piece 70 will remain off valve seat 68 so long as the valve 45 38 remains open, and so long as pilot 80 can ignite from pilot 35.

The operation of the system is controlled by a humidostat 82 which is located at some convenient point in the premises to be humidified. The 45 particular character of the humidostat is of no importance in this invention except that it should be of such nature as to be capable of switching on and off a 110 volt current. As illustrated in the drawings, it may comprise an elongated strip 50 83 of material which is sensitive to humidity changes, that is one which expands and contracts with such changes. This strip is anchored at one extremity to the end of a lever 84 which is pivoted at 85 to a suitable support and is adjustable by means of a screw 86. The strip runs over guides 87 and is connected at its opposite extremity to one arm of a lever 88 pivoted at 89 to the support. The opposite arm of the lever is attached to a spring 90 which maintains the strip 83 under tension. The lever 88 has a downwardly projecting arm 91 with a bifurcated extremity that engages a pin on a bracket 92 which is pivoted at 93 to the support. The bracket 92 carries a glass capsule 94 within which there is a globule 65 of mercury 95 that is adapted to bridge contacts in one end of the capsule connected with flexible electric conductors 96 and 97. These conductors have binding posts 98 and 99. An electric conductor 100 extends from binding post 99 to line 70 wire 101, while the conductor 102 is connected with binding post 98. Conductor 102 extends to one end of solenoid coil 44. From the other end of that coil a conductor 103 leads to line wire 104. Branch conductors 105 and 106 extending 75

from conductors 102 and 103 carry current to the motor 13.

Inasmuch as the heat from pilot 35, if continued for a long period of time without operation of the apparatus, might dry up the water in the system, I provide a by-pass pipe 107 around the valves 42 and 45, in which there is a needle valve 108 that is set to permit only a very limited flow of water, which passes through the system 10 constantly and insures a supply of water at all times in the pan 14 and in the water conductors 16 and 18.

The various parts of the apparatus are shown in Fig. 2 in the operating position. At such times 15 water flows into the heater through pipe 20, valve 42 being open. A comparatively small quantity of water is also flowing through pipe 107. The pressure of the water in the pipe 20 is transmitted through branch pipe 46 to the lower side 20 of diaphragm 48, and as a result that diaphragm is in the raised position illustrated, and consequently the diaphragm 51 is also raised from its seat 52 to the illustrated position, permitting gas to flow into valve 39, which is maintained open to 25 a slight extent. If the water in return pipe 18 becomes heated above a predetermined degree, the expansible tube 61 is lengthened sufficiently to permit spring 67 to raise valve piece 59 and reduce the rate of flow of the gas. The water thermostat is so set by the pointer 66 as to prevent the water in the pan 14 from reaching boiling temperature. Valve 40 is maintained open, as previously explained, provided the pilot 35 is burning.

At this time the lever 88, 89 and associated parts 35 of the humidostat will be in the position illustrated. The conductors 96 and 97 will be connected by the mercury globule 95 and the motor 13 will be running. The fan 10 will therefore be inducing a flow of air, taken from the premises, and having a humidity below that desired. The finely divided warm water on the screen 24 will be taken up by the air passing through the screen, this absorption of moisture being facilitated by the heated condition of the water. At 40 the same time the air passing through the screen will be raised in temperature a few degrees because of the heated water. This moistened air then flows around the jacket 15 of the water heater and around the flue 30. Thus, it has its temperature increased, and therefore its relative humidity decreased. At this higher temperature the air passing over the surface of the water in the pan is capable of absorbing more moisture than if it had not been heated in this intermediate stage. 45 Hence, when the air contacts the surface of the water in pan 14, as indicated by the arrows in Fig. 2, it is in favorable condition to absorb further moisture from the water in the open pan, that water being quite hot. The humidified air 50 then passes out of the unit through opening 32 and into the premises.

Upon the humidity of the air in the premises reaching the desired point, the humidity responsive strip 83 in the humidostat will be lengthened 55 by expansion, and the spring 90 will then swing the lever 88 in the anti-clockwise direction, when the capsule 94 will be turned on the pivot 93 to the dotted line position to cause the globule 95 to move to the right hand end of the capsule, thereby 60 breaking the electrical connection between conductors 96 and 97. The water valve 43 will then close, and the motor 13 will stop. Water pressure below diaphragm 48 will then be relieved permitting pin 50 to descend. Diaphragm 51 65 will then descend and engage annular seat 52,

and gas will flow through bleed hole 53 to equalize the pressure above and below the diaphragm. By this means the flow of gas into the water heater will be stopped. Thermostatic metal strip 78 will then straighten out, causing the valve disc 70 5 to engage seat 68 and open the passage into tube 79. There will then be no activity in the unit except for the burning of pilot 35 and the flow of a slight amount of water through by-pass 107, then through the heater, and out by way of the 10 overflow 21 and screen 24 to the drain pipe 29.

During the operation of the unit the water passing down over the screen in a finely divided state is cooled by evaporation and tends to approach the wet bulb temperature of the air introduced into the apparatus by the fan. Let us say, for example, that the air introduced by the fan (which is withdrawn from the quarters being conditioned) is in a state of temperature and humidity considered desirable for living quarters, 20 namely 70° dry bulb temperature and 40% relative humidity, which corresponds to a wet bulb temperature of 56°. With small amounts of water passing over the screen, by the time the water reaches the bottom of the screen it will be cooled 25 to this 56° wet bulb temperature of the entering air. Therefore, if the water in the water supply is initially at 56°, the waste water will go out at the temperature the water initially entered the heater, thus resulting in no loss whatsoever to 30 the sewer. If the water happens to be at a temperature initially below 56° the loss of heat to the sewer is minimized. If the water is fortunately at a temperature above 56°, which may prevail during the early part of the humidifying 35 season, some heat is actually extracted from the water, thus resulting in an actual gain of heat by the air at the expense of the water. The city water system then furnishes some of the heat for the house. This feature promotes economy in 40 operation.

It will be observed that the apparatus provides humidification in two steps, the first step being when the air passes through the screen, and the second step being when the air passes over the 45 surface of the body of water, from the overflow of which the screen is moistened. The humidifying also takes place according to the counter-flow principle, which is superior in economy, so far as the amount of humidifying surface required is concerned, to humidification taking place according to the parallel flow principle. By this I mean the less humid entering air, which therefore has a lower vapor pressure than the leaving air, is brought into contact with the cooler water, which has less vapor pressure than the hotter water, while the leaving air with a higher vapor pressure, comes into contact with hotter water which possesses a still higher vapor pressure. This gives a greater average difference 50 in vapor pressures, which is the motive power to produce humidification, than if the water and the air travelled along parallel paths. 55

In Fig. 3 I have shown a modification designed to be employed primarily in buildings of considerable size. In this form of the invention I use an open pan 110 supplied with water from a service pipe 111, the water in the pan being maintained at a predetermined level by means of float valve 112. The water in the pan is heated by 60 steam coil 113 fed by pipe 114 from a boiler 115, there being a return pipe 116 from the coil to the boiler.

Water is drawn off from the pan 110 through a pipe 116 from a point just above the steam coil 75

113. A water pump 117 to which pipe 116' is connected forces the heated water through a pipe 118 into a set of spray nozzles 119, which provide a cloud of spray in the path of air delivered 5 by a blower 120 which is mounted in an air conductor leading from the premises. As soon as the air is humidified in this manner it passes through an eliminator 121 of conventional form, by which water that is not thoroughly vaporized is removed. Thereafter the moistened air passes between the coils of a steam radiator 122, by means of which the air is further heated. It is then deflected downwardly by a baffle 123 and caused to pass close to the surface of the hot water in 10 pan 110, which action provides a second stage of humidification, as in the first described form of the invention. The radiator 122 may be supplied with steam through a pipe 124 branching from pipe 114, and the condensation water may 15 be returned to the boiler by a pipe 125 connected with pipe 116. The air when fully humidified is conducted back to the premises by an air conductor 126.

25 In the drawing no means for automatically controlling the apparatus of Fig. 3 is shown, but it will be obvious that such a means can be provided, particularly for the pump 117 and the blower 120, through electrical connections for the electric motors driving those elements. The electrical connections may be made and broken by 30 a humidostat, in the same manner as disclosed in the modification of Figs. 1 and 2. The automatic control means may also be caused to cut on and off the steam to coils 113 and 122, if desired, as will be obvious to those skilled in the art.

35 Variations from the described structures may be employed. Accordingly I desire it to be understood that the scope of the invention is to be regarded as defined exclusively by the appended 40 claims, rather than by the foregoing description or the accompanying illustrations.

Having thus described my invention, I claim:

1. A method of humidifying and warming air, which comprises humidifying the air by causing 45 it to move through a curtain of finely divided hot water, warming the thus humidified air by passing it over the heater which provides the hot water, and then further warming and humidifying the air by passing it over the surface of the 50 water in a reservoir fed by the heater, from which reservoir is drawn said curtain of finely divided hot water.

2. In a humidifier, a water heater having a water coil, an open pan in circuit with said coil, a 55 screen arranged below the pan and adapted to receive water overflowing from the pan, and means for causing air to flow over said screen, then over the water heater, and finally over the surface of the water in the said pan, whereby the cold air 60 is moistened and warmed, then further warmed, and finally further moistened and warmed.

3. In combination, a humidostat, a humidifier 65 embodying a water heater, a conductor for water and a conductor for fluid fuel both leading to said heater, means for causing the air to be humidified to pass in contact with water heated in said heater, means actuated by the water in the water conductor for controlling the flow of fuel in the fuel conductor, and a valve in the water conductor operatively connected with said humidostat to be opened when the humidostat calls for 70 humidification.

4. In combination, a humidostat, a humidifier 75 embodying a water heater and a blower, an electric motor for operating said blower, a conductor for water and

for water and a conductor for fluid fuel both leading to said heater, said blower causing the air to be humidified to pass in contact with water heated in said heater, means actuated by the water in the water conductor for controlling the 5 flow of fuel in the fuel conductor, an electric valve in the water conductor, and electrical connections between said humidostat and said motor and between said humidostat and said electric valve whereby said blower may be started and said wa- 10 ter and fuel may be turned on when said humidostat calls for humidification.

5. In a humidifier, a water heater comprising a jacket and a water coil, an open pan mounted above the jacket, a connection from the coil to 15 the pan and a return connection from the pan to the coil, a screen arranged below the pan and adapted to receive water overflowing from the pan, means for passing air through said screen, and then over the jacket of the water heater, and 20 finally over the surface of the water in the pan.

6. In a humidifier, a water heater comprising a jacket, an open pan mounted above the jacket, a connection from the heater to the pan and a return connection from the pan to the heater, a 25 screen arranged below the pan and adapted to receive water overflowing from the pan, means for passing air through said screen, then over the jacket of the water heater, and finally over the surface of the water in the pan, and means for 30 deflecting the air downwardly as it passes over the pan, whereby ripples are produced in the water in the pan and the heated water therein is caused to give up additional moisture.

7. In combination, a humidifier embodying a 35 water heater, a conductor for water and a conductor for fluid fuel both leading to said heater, means for causing the air to be humidified to pass in a current in contact with water heated in said heater, means controlled by the water 40 pressure in the water conductor for turning on or off the flow of fuel in the fuel conductor, an electric valve in the water conductor, and means for operating said electric valve by remote control.

8. In combination, a humidifier embodying a 45 water heater, a conductor for water and a conductor for fluid fuel both leading to said heater, means for causing the air to be humidified to pass in a current in contact with water heated in said 50 heater, means controlled by the water pressure in the water conductor for turning on or off the flow of fuel in the fuel conductor, and means arranged for actuation at a point remote from said water heater for varying the pressure in said water conductor.

9. In combination, a humidifier embodying a water heater and a blower, an electric motor for operating said blower, a conductor for water and a conductor for fluid fuel both leading to said heater, said blower being arranged to cause the 60 air to be humidified to pass in contact with water heated in said heater, and means actuated by the water in the water conductor for controlling the flow of fuel in the fuel conductor, an electric valve in the water conductor, and a remote control for said electric valve and said motor whereby said blower may be started and said water and fuel may be turned on simultaneously.

10. A method of humidifying air, which comprises introducing hot water into an open pan, 70 removing water from one end of the pan and causing it to take the form of a curtain of finely divided particles extending downwardly from the pan, moving a column of air through the curtain and beneath the pan to the opposite end thereof,

and then back over the surface of the heated water in the pan to absorb further moisture.

11. A method of humidifying air, which comprises introducing hot water into an open pan, removing water from one end of the pan and causing it to take the form of a curtain of finely divided particles extending downwardly from the

pan, moving a column of air through the curtain and beneath the pan to the opposite end thereof, heating the air after it leaves said curtain, and then causing it to flow back over the surface of the heated water in the pan to absorb further moisture.

WILLET E. STARK.
